Attorney

UNITED STATES PATENT OFFICE.

JOSEPH LEITNER, OF MANITOU, COLORADO.

WAFFLE IRON.

Application filed July 2, 1924. Serial No. 723,688.

This invention is in the way of a set of waffle irons, and the object is to provide such irons which will supply the cooked waffles of a meniscus form in cross section and with a surface design imitating the Egyptian pyramids.

In the drawing—

Figure 1 is a plan view;

Figure 2 is a transverse section;

10 Figure 3 is a plan view of a waffle as formed by this set of irons;

Figure 4 is a transverse section through the waffle as formed.

This invention includes the usual heavy, 15 annular base casting 1, adapted to set over the hot plate of the stove. This base has handle and hinge cut-outs 2 and 3 respectively, at opposite sides thereof. Two waffle irons 4 and 5 are provided, the same each 20 having a handle 6 adapted to overlap in the handle cut-out 2 of the base, and each having a laterally extended hinge lug 7 opposite to the handles, hinged together at 8 and adapted to lie within the hinge cut-out 3 of the 25 base. The irons 4 and 5 are spaced apart for the required thickness of the waffles to be cooked, and they each have outer annular sections 9 curved in one direction, and centers 10 curved in the opposite direction.

This structure imparts a corresponding form 30 to the waffles so that they stand balanced, and so that they do not lie flat on the plate when served. The inner surfaces of the irons 4 and 5 are patterned and cut with a plurality of designs in similitude of pyramids 35 11 to impart a design to the waffles.

While I have herein described a certain specific manner and method of constructing and assembling the elements of my invention, it is understood that I may vary from the same in minor details, not departing from the spirit of my invention, so as best to construct a practical device for the purpose intended, as defined in the appended claim.

45 I claim:

A waffle iron comprising parallel, complementary mold sections, each of said mold sections comprising an outer annular portion having an outer free edge, and a center 50 portion, the said annular portion, when the sections are in their normal, closed position, being gradually outwardly and downwardly curved to its outer, free edge, and said center portion being downwardly depressed.

55 In testimony whereof I affix my signature.

JOSEPH LEITNER.
